UNITED STATES PATENT OFFICE.

FRANK J. LOVIN, OF MAHNOMEN, MINNESOTA.

ARTICLE-HOLDER.

1,211,463.

Specification of Letters Patent.

Patented Jan. 9, 1917.

Application filed June 4, 1915. Serial No. 32,228.

To all whom it may concern:

Be it known that I, FRANK J. LOVIN, a citizen of the United States, residing at Mahnomen, in the county of Mahnomen and State of Minnesota, have invented certain new and useful Improvements in Article-Holders, of which the following is a specification.

My invention relates to article holders and more particularly to an improved pocket-attached book, pen and pencil holder.

A primary object of the invention is to combine in a single organization and to construct from a single strand of resilient wire, a means for releasably fastening the device or holder against accidental displacement while in use; and a means for yieldably and releasably fastening a book or other article, pen and pencil in such associated relation as to permit, if desired, of independent use without affecting in any way the connection between the article itself and the support means therefor.

The invention may be said to consist in the novel construction, combination and arrangement of parts to be hereinafter more fully described and particularly pointed out in the appended claims.

In the drawings, hereto annexed: Figure 1 is a front elevation of my improved device illustrating the manner in which various articles are held thereby; Fig. 2 is a rear elevation; Fig. 3 is a plan view; and Fig. 4 is an end view.

Like numerals of reference designate like or corresponding parts throughout the several views.

Before proceeding with a description of the drawings, I desire to call particular attention to the fact that while I have evolved my invention as a means for holding booklets, pens and pencils, the same, if desired, may be readily utilized as a fastening and holding means for other articles or devices susceptible of association therewith.

Referring now to the drawings by numerals, 1 designates as an entirety the article holder which, in its preferred embodiment is constructed from a single strand of resilient wire bent to form gripping jaws 2 and 3, an actuating coil 4, and a retaining means 5, the jaws affording a means whereby the booklet or other article is held in place; the coil, a means whereby a pen or pencil receiving tube 6 is held in place, and the retaining means, a means whereby the

device as an entirety is yieldingly fastened to the outside top edge of a vest or other wearing apparel pocket.

The device, as before stated, is constructed from a single strand of resilient wire, and in order that a clear understanding may be gained I shall proceed to more specifically outline the various bends and twists formed in the wire strand necessary to the provision of the parts designated generally 2, 3, 4 and 5.

7 designates the point at which the terminals of the wire strand meet. In following the course of the wire strand from the point 7, 8 designates a portion of the gripping jaw. The straight line portion 8 is bent as indicated at 9 to extend vertically as indicated at 10, the vertically extended portion being bent as at 11 upon itself or as indicated at 12 to extend parallel with that portion 10 aforesaid. The portion 12 is bent as at 13 to extend in a straight line as indicated at 14, parallel with the straight line portion 8. Straight line portion 14 at its opposite end from that bent as at 13 is coiled as indicated at 15 to form a portion of the retaining coil 4. The coiled portion 15 terminates at a point equi-distant from the terminals of the retaining coil 4, the wire strand from such intermediate point extending in a straight line or as indicated at 16 again parallel with the straight line portion 14 to a point 17 where it is bent to extend vertically as at 18, said vertically extended portion being in turn bent as at 19 to depend as at 20 and extend parallel with the vertical portion 18 to a point 21 where it is again bent to extend upwardly as at 22 to a point 23 approximately equi-distant from the bends 95 designated respectively 19 and 17. From the point 23 the wire strand is bent forwardly and downwardly to extend as at 24 to a point 25 where it is again bent to extend in a horizontal plane or as indicated at 26. Portion 26 is bent as at 27 to extend vertically as at 28 where it is again bent as at 29 to form the upper portion of the coil 4, said upper portion being designated 30. The opposite end of the coiled portion 30 extends in a straight line as at 31 to the point 7 where it abuts the straight line portion 8 previously noted.

The portions of the wire strand designated 31, 8, 10, 11, 12, 13 and 14 constitute the gripping jaw 2, the portions of the wire strand designated 16, 17, 18, 19, 20, 21, 22,

23, 24, 25, 26, 27 and 28 constitute the gripping jaw 3, the portions of the wire strand designated 15 and 30 constitute the retaining coil 4; and the portions of the wire strand designated 28, 27, 26, 25, 24, 18, 16, 30 and 15 constitute the retaining means whereby the article itself is held in place in the manner aforesaid. The portions 8, 31, and 14 are held in parallel spaced relation by a web structure 32 which embraces the respective mentioned portions and engages the portion 12 as indicated at 33 whereby to preclude longitudinal movement of the web portion. The web portion also affords a flat bearing surface against which the book or other device to be held by the jaws 2-3 may abut.

Tube 6 is provided with a flared mouth 34 to facilitate insertion of a pen or pencil therein, and is instruck at a point approximately equi-distant from its ends to provide a retaining tongue 35 which, by its yielding contact with the pen or pencil inserted within the tube will afford a yielding retaining means therefor.

25 That portion of the wire strand designated 26 is bowed or offset to afford with the portion designated 16 and the booklet fastened by the jaws 2 and 3, a means whereby a second pen or pencil may be held in place.

In actual practice, the device as an entirety is fastened over and upon the top edge of the vest pocket, the retaining means 5 engaging with the vest pocket material to 35 hold the device in place. When thus positioned the jaws 2 and 3 may be relatively spread to permit a booklet or other article to be arranged therebetween and, by the compression obtained through the spring 40 action generated in the coil 4, said article or booklet held firmly in place and within the pocket. The coil 4 affords a retaining means for the protector tube 6, which tube, by reason of the instruck tongue 35 will receive either a pen or pencil and, by reason 45 of the yielding engagement therewith, hold said pen or pencil in place. The bowed portion 26 may also be utilized as a pen retaining means as before pointed out.

50 From the foregoing, taken in connection with the accompanying drawings it is evident that the device as an entirety may be quickly and easily attached and detached, if

desired; that the entire device is constructed from a single strand of resilient wire bent 55 in the manner aforesaid; and that the retaining means for the device also forms a part of the jaw 3 whereby the book or other article may be held properly in place.

In reduction to practice, I have found that 60 the form of my invention, illustrated in the drawings and referred to in the above description, as the preferred embodiment, is the most efficient and practical; yet realizing that the conditions concurrent with the 65 adoption of my device will necessarily vary, I desire to emphasize the fact that various minor changes in details of construction, proportion and arrangement of parts may be resorted to, when required, without sacrificing any of the advantages of my invention, as defined in the appended claims.

Having thus fully described my invention, what I claim as new and desire to secure by Letters Patent, is:—

75

1. In a combined pocket-attached book, pen and pencil holder, a tube, a single strand of resilient wire bent to form a coil, gripping jaws formed at each side of the coil, the coil providing a means whereby said jaws are normally held in engaging proximity and also providing a retaining means for the tube, a retaining means for the article itself formed upon one of said jaws, the said retaining means being bowed to afford 80 with the remainder of the jaw of which it is a part a means whereby an article may be held in place, substantially as described.

2. In a combined pocket attached book, pen and pencil holder, a single resilient 90 strand of wire bent to form a coil, triplicate gripping jaws, two of which are connected at their ends and formed into a right angular flat face for co-action with the remaining jaw to clasp the book, the connected jaws 95 being slightly separable to receive a pencil and to engage the material of a pocket, and a tube held within the convolutions of the coil.

In testimony whereof I affix my signature 100 in presence of two witnesses.

FRANK J. LOVIN.
